UNITED STATES PATENT OFFICE.

JAKOB BECKER AND JOHN P. BECKER, OF DETROIT, MICHIGAN.

PIANO-CASE.

SPECIFICATION forming part of Letters Patent No. 252,717, dated January 24, 1882.

Application filed October 1, 1881. (No model.)

To all whom it may concern:

Be it known that we, JAKOB BECKER and JOHN P. BECKER, of Detroit, in the county of Wayne and State of Michigan, have invented 5 an Improvements in Pianos, of which the following is a specification.

The nature of our invention relates to certain new and useful improvements in that class of instruments known as "upright pianos," by 10 means of which a much greater volume of sound is obtained, and by means of which a swelling or diminishing of such volume is produced, whereby an effect similar in some degree to the swell of an organ is had.

15 The upright piano—that is to say, a piano in which the strings are vertical instead of horizontal, as in square or in grand pianos, is becoming very popular, because, on account of its shape and construction, it takes up so much 20 less room than those of the other classes; but, as such uprights are usually placed against the wall of a room, the saving in space occupied is obtained at the expense of the volume of 25 sound which, impinging against the wall against which the piano is placed, becomes deadened, as the sound-waves are broken by such impingement.

The object of our invention is to remedy this serious objection to the use of upright pianos, 30 and to render them just as effective instruments as those of the other classes named; and the invention consists in the improvement, as more fully hereinafter described.

Figure 1 is a vertical cross-section through 35 the center of an upright piano. Fig. 2 is a plan view of the same with the top removed.

In the accompanying drawings, which form a part of this specification, A represents an upright piano, having the customary sounding- 40 board, a, and apertured back wall or panel, b, for the passage of the sound-waves.

To the rear side of the piano, or, more properly, to the apertured back thereof, is secured 45 a resonant chamber, B, formed of a metallic or wooden sheet-wall, C, preferably in the form of the half of an ellipse, a bottom, D, and a hinged cover, E.

To the side edges of the wall C are secured 50 vertical stiffening ribs or bars, G, having openings for the passage of screws or other fasten-

ing devices that serve to secure the resonant chamber to the back of the piano. A stiffening rib or rail, F, secured to the upper edge of the wall C, serves for the attachment of the hinges of the cover E.

The mechanism for raising the cover E and regulating the passage of sound from the resonant chamber comprises the oblique lever H, the short lever, J, the pedal I, the short link d for connecting the two levers, and the rod K, 60 connected with the longer arm of the lever H and the cover E, as is clearly shown in Fig. 1. The treadle I projects through the front of the piano-casing, and is preferably located between the ordinary loud and soft pedals of the instrument, so as to be within convenient reach of the player. The lever J is pivoted beneath the piano-casing, and the long lever, H, has its fulcrum in the apertured back of the instrument and extends obliquely into the resonant 70 chamber.

We are aware that it is not new to provide an organ with a vertical resonant chamber located in rear of the reeds or sound-producing devices, and that an upright piano has 75 been constructed with a resonant chamber arranged inside the casing of the instrument, in close contact with the sounding-board.

We are also aware of the existence of an upright piano in which a swell lid, arranged directly above the string-chamber, is raised by 80 means of a pedal and connections.

Our invention differs from the above, because we use a resonant chamber which is attached directly to the rear wall of an ordinary upright 85 piano, and the swell-lid of said resonant chamber is actuated by simple and convenient devices requiring no cutting of the casing of the instrument in fitting said parts.

What we claim as our invention is— 90

An upright piano having an attachable resonant chamber, provided with a swell-lid secured to the apertured rear wall of the instrument, as and for the purpose set forth.

JAKOB BECKER.
JOHN P. BECKER.
